UNITED STATES PATENT OFFICE.

PETER J. BALTES, OF OSWEGO, NEW YORK, ASSIGNOR OF ONE-HALF TO
JAMES B. DONNELLY, OF SAME PLACE.

LUBRICATOR.

SPECIFICATION forming part of Letters Patent No. 295,474, dated March 18, 1884.

Application filed January 9, 1884. (No model.)

To all whom it may concern:

Be it known that I, PETER J. BALTES, of Oswego, in the county of Oswego, in the State of New York, have invented new and useful 5 Improvements in Lubricators, of which the following, taken in connection with the accompanying drawings, is a full, clear, and exact description.

This invention relates to the class of lubricators which are applied to connecting-rods or pitmen directly over the wrist-pin, and have over the lubricant-duct a gravitating valve raised automatically from its seat by the thrust of the rod or pitman.

15 The invention consists in certain peculiarities in the detail construction of the lubricator and certain devices connected therewith, as hereinafter more fully described, and specifically set forth in the claims.

20 In the annexed drawings, Figure I is a vertical section of my improved lubricator, and Fig. II is a top view of the same.

Similar letters of reference indicate corresponding parts.

25 C denotes the lubricant-cup, having a base, B, provided on its under side with a screw-threaded boss, d, by which it is screwed into a socket in the rod or pitman to be lubricated, a lubricant-duct, a, being extended through 30 the base B and the boss, as illustrated in Fig. I of the drawings. The upper end of said duct is provided with a valve-seat, a', on which is seated a gravitating valve, v.

In order to admit of introducing the valve 35 into the cup, and to obtain convenient access to the valve-seat for grinding and repairing the same, I make the cup C detachable from the base B, by providing the latter with an upward-projecting screw-threaded boss, d', and 40 forming the cup with a bottom having a screw-threaded orifice, e, into which the boss d' is screwed. The valve v is guided by a stem, c, rising from said valve and passing through a channel in a guide, b, which is sustained in the 45 cup by radial arms extended therefrom and rigidly attached to or integral with the wall of the cup.

To facilitate the repairs of the valve, I provide the upper end of the valve-stem c with a 50 transverse slot, s, for the application of a screw-

driver, by which to turn and grind the valve in and to its seat, and in order to obtain ready access to the said valve-stem, I make the cap or entire top A removable by providing it with an overhanging downward-projecting flange, f, which is screw-threaded and screws onto the exterior of the end of the cylinder or body of the cup, the edge of the cover being milled, as illustrated in Fig. II of the drawings, to facilitate the manipulation thereof.

To prevent the cover A from working loose from the cup, I provide the edge of the former with a notch, n, and attach to the exterior of the cup a latch, l, held automatically in engagement with the notch, and yielding sufficiently to allow it to be forced out of the notch when desired to remove the cover A. Vertically through the aforesaid cover works a screw, r, which is directly over the end of the valve-stem c. By a suitable knob on the outer end of the 70 said screw the same can be turned so as to enter the cup to a greater or less depth, the distance between the lower end of the screw r and upper end of the valve-stem c controlling the lift of the valve v, and consequently the egress 75 of the lubricant from the cup C.

D represents a stationary graduated dial arranged concentric with the aforesaid regulating-screw r on the top of the cover A, and p is a pointer fixed to the screw r, or to its knob, and 80 having its free end over the aforesaid dial, to indicate thereon the degree of movement of the regulating-screw r, and consequently the amount of play allowed to the valve-stem and valve, which play controls the flow of the lubricant from the cup to the parts to be lubricated.

Having described my invention, what I claim as new, and desire to secure by Letters Patent, is—

1. The combination of the base B, provided with the screw-threaded bosses d d', and with the channel a and valve-seat a' in the same, the cup C, provided with the screw-threaded orifice e in its bottom, and the guide b above the bottom, and the valve v, having the stem c, 95 sliding in the said guide, substantially as specified and shown.

2. The combination, with the lubricant-cup, of a cap screwed onto the top thereof, and having an overhanging flange provided with a 100

notch, and a latch connected to the exterior of the cup and adapted to engage said notch, substantially as described and shown.

3. In combination with the cup C, valve *v*, provided with the stem *c*, and the regulating-screw *r*, the dial D, arranged on top of the cup concentric with the regulating-screw, and the pointer *p*, fixed to said screw, substantially as described and shown, for the purpose set forth.

In testimony whereof I have hereunto signed my name and affixed my seal, in the presence of two attesting witnesses, at Syracuse, in the county of Onondaga, in the State of New York, this 21st day of December, 1883.

PETER J. BALTES. [L. S.]

Witnesses:

C. H. DUELL,
F. H. GIBBS.
